(57) **CLAIM**

The ornamental design for an automatic drip coffeemaker, as shown and described.

DESCRIPTION

FIG. 1 is a perspective view of an automatic drip coffeeemaker showing our new design;

FIG. 2 is a top plan view of the automatic drip coffeeemaker shown in FIG. 1.

FIG. 3 is a front end view of the automatic drip coffeeemaker shown in FIG. 1.

FIG. 4 is a rear end view of the automatic drip coffeeemaker shown in FIG. 1.

FIG. 5 is a right side view of the automatic drip coffeeemaker shown in FIG. 1.

FIG. 6 is a left side view of the automatic drip coffeeemaker shown in FIG. 1.

FIG. 7 is a perspective view of an automatic drip coffeeemaker showing a second embodiment of our new design;

FIG. 8 is a top plan view of the automatic drip coffeeemaker shown in FIG. 7.

FIG. 9 is a front end view of the automatic drip coffeeemaker shown in FIG. 7.

FIG. 10 is a rear end view of the automatic drip coffeeemaker shown in FIG. 7.

FIG. 11 is a right side view of the automatic drip coffeeemaker shown in FIG. 7.

FIG. 12 is a left side view of the automatic drip coffeeemaker shown in FIG. 7.

FIG. 13 is a perspective view of an automatic drip coffee-maker showing a third embodiment of our new design;
FIG. 14 is a top plan view of the automatic drip coffeeemaker shown in FIG. 13.
FIG. 15 is a front end view of the automatic drip coffee-maker shown in FIG. 13.
FIG. 16 is a rear end view of the automatic drip coffeeemaker shown in FIG. 13.
FIG. 17 is a right side view of the automatic drip coffee-maker shown in FIG. 13.
FIG. 18 is a left side view of the automatic drip coffeeemaker shown in FIG. 13.
FIG. 19 is a perspective view of an automatic drip coffee-maker showing a fourth embodiment of our new design;
FIG. 20 is a top plan view of the automatic drip coffeeemaker shown in FIG. 19.
FIG. 21 is a front end view of the automatic drip coffee-maker shown in FIG. 19.
FIG. 22 is a rear end view of the automatic drip coffeeemaker shown in FIG. 19.
FIG. 23 is a right side view of the automatic drip coffee-maker shown in FIG. 19.
FIG. 24 is a left side view of the automatic drip coffeeemaker shown in FIG. 19.
FIG. 25 is a perspective view of an automatic drip coffee-maker showing a fifth embodiment of our new design;

FIG. 26 is a top plan view of the automatic drip coffeeemaker shown in FIG. 25.
FIG. 27 is a front end view of the automatic drip coffee-maker shown in FIG. 25.
FIG. 28 is a rear end view of the automatic drip coffeeemaker shown in FIG. 25.
FIG. 29 is a right side view of the automatic drip coffee-maker shown in FIG. 25.
FIG. 30 is a left side view of the automatic drip coffeeemaker shown in FIG. 25.
FIG. 31 is a perspective view of an automatic drip coffee-maker showing a sixth embodiment of our new design;
FIG. 32 is a top plan view of the automatic drip coffeeemaker shown in FIG. 31.
FIG. 33 is a front end view of the automatic drip coffee-maker shown in FIG. 31.
FIG. 34 is a rear end view of the automatic drip coffeeemaker shown in FIG. 31.
FIG. 35 is a right side view of the automatic drip coffee-maker shown in FIG. 31; and,
FIG. 36 is a left side view of the automatic drip coffeeemaker shown in FIG. 31.
The broken lines in the drawings are for illustrative purposes only and form no part of the claimed design.
